United States Patent Office

CHARLES MOLE, OF PEMBROKE TERRACE, REGENT'S PARK, LONDON,
ENGLAND.

Letters Patent No. 71,898, dated December 10, 1867.

IMPROVEMENT IN BOOTS AND SHOES.

The Schedule referred to in these Letters Patent and making part of the same.

TO ALL WHOM IT MAY CONCERN:

Be it known that I, CHARLES MOLE, of Pembroke Terrace, Regent's Park, London, boot and shoe manufacturer, have invented "Improvements in the Manufacture of Boots and Shoes;" and I do hereby declare that the following is a full and exact description thereof, reference being had to the accompanying sheet of drawing, making a part of this specification, and to the figures and letters of reference marked thereon, similar letters of reference denoting similar parts where such parts appear or may be seen at each of the figures respectively.

The nature of my invention consists in so making the heel of a boot or shoe that the wearer may, with great facility, turn the lower part thereof, and thus bring an uneven portion of the bottom or tread into the position previously occupied by a part of the tread, which, from being subjected to the greatest wear, shall have become uneven with the remainder of the bottom of the heel.

I am aware that movable and revolving heels have, in many instances, been applied to boots and shoes for the purpose above set forth, but in every case the methods adopted have labored under the disadvantages of being too expensive, too complicated, or otherwise ineffective.

I construct my boot-heel in two parts, and screw or otherwise fasten a disk or plate of brass, bronze, or other suitable metal or material, on to the under side of the top part, and a plate of the same material on to the upper surface of the lower part, so that, when the two parts of the heel are placed together, these two plates are brought into juxtaposition. In the centre of one of the metal plates, the top or bottom one, indifferently, I cut a square hole, passing either through or only partially through the thickness of the plate, and on the other plate, which is to be brought into juxtaposition with it, I form a projection, the shape of which will be the exact counterpart of the hole in the first-mentioned plate. The two parts of the heel will be secured together by a pin passing through a hole in the centre of the lower part of the heel, and which may either form part of the top-plate, in which case its shoulder may form the square or other projection which is to take into the hole or slot made in the under plate, and its lower end will be screw-threaded, to receive a flat nut of brass or other suitable metal or material, which, when the two plates are brought close together, will be countersunk in the bottom or tread of the heel. But this pin may also pass up from the tread of the heel; in which case its head will take the place of the nut above mentioned, and the pin will be screw-threaded at that part which passes through the hole in the centre of the top and bottom-plate, which hole will also be screw-threaded, and thus the two parts of the heel will be drawn tightly together. It will be evident that if the pin or screw forms part of the top-plate the lower plate only will have a hole through its centre. This method of fastening is much more certain and durable than any spring-fastening, and also less expensive.

Figures 1, 2, 3, and 4, of the annexed sheet of drawing, illustrate the construction of a man's boot-heel made according to my invention, fig. 1 being a vertical section through the centre of boot-heel, and figs. 2, 3, and 4 detached parts of same. *a*, top-plate, (shown detached at fig. 2;); *b*, bottom-plate, (shown detached at fig. 3;); *c*, pin or screw passing from top-plate through lower plate and bottom part of heel, where it is secured by the nut *d*, which has two slots, *e*, (see fig. 4,) in order that it may be unscrewed with a key provided for that purpose; *f* (figs. 1 and 2) is the projecting square piece which takes into the sunken square *g* of the plate *b*, (see figs. 1 and 3;); *h*, lower part of heel; *i*, tread or bottom of heel; *j*, screws fastening plate to heel, and *k*, hole for passage of pin *c*.

The action is as follows: When it is desired to turn the heel and bring another part of the tread into the place most subject to wear, the nut *d* is unscrewed from the pin *c*, either wholly or enough to permit the lower part *h* of the heel to be moved sufficiently from the top part or plate *a* that the projecting square *f* may come out of the sunken square *g*, leaving the part *h* free to be turned round, right or left, and when it has received one quarter turn, the projection *f* can drop again into the sunken square *g*, and the whole be again secured in position by screwing up the nut *d*, or the part *h* may receive another quarter turn, and be then secured.

Figures 5, 6, 7, and 8 illustrate a man's boot-heel made according to my invention, the fastening-screw or pin *c* passing up from beneath, and not forming part of the top-plate *a*. Fig. 5, vertical section through centre of boot-heel. Fig. 6, top plan view of bottom part of heel; *b*, bottom plate or disk; *g*, sunken square; *h*, boot-heel. Fig. 7, bottom plan view of top part of heel; *a*, top plate; *f*, projecting square; *l*, top part of heel. It

will be observed that in this arrangement the plates or disks *a* and *b* are countersunk in their respective parts of the heel, and that their rims do not appear on the exterior, as at fig. 1. Fig. 8, pin *c* detached; *m*, slot for screwing up. Here the screw *c* passes from the tread *i* up through the lower part *h* of the heel and through the plates *b* and *a*, the central holes in which are screw-threaded. By unscrewing the pin *c* two or three turns the projection *f* may be drawn out of *g*, and the lower part of the heel become free to be turned as may be required.

Figure 9 illustrates the application of the last-described arrangement to the heel of a lady's boot. The plates *a* and *b* may be placed near the top of the heel, in the centre or elsewhere, as may be desired.

My experience leads me to believe that less than a quarter turn of the lower part of the heel will rarely be required, and I would therefore usually use a square projection and hole or slot; but my projecting piece may be made sexagonal, octagonal, or present any desired number of sides, so that the slot-hole or countersunk part which is to receive it be of precisely the same shape.

And having now described the nature of my said invention, and the means by which I carry it into practical effect, I would have it understood that I do not confine myself to the exact details herein given, nor to any precise dimensions of the several parts, as such may be varied and modified without departure from my invention; but

What I claim as of my invention, and desire to secure by Letters Patent, is—

The manufacture of a movable boot-heel in two parts, to be adjusted in different positions by means of a single central projection taking into a single slot-hole or countersunk part, and secured in position by means of a central screw or pin, whether such projection and hole or countersunk part be square or many-sided, and no matter what the shape of these sides, so that the shape of the projection and that of the hole which is to receive it be identical, the whole substantially as hereinbefore described and illustrated on the annexed sheet of drawing.

CHARLES MOLE.
